UNITED STATES PATENT OFFICE.

HENRY FORCE GAREY, OF BALTIMORE, MARYLAND.

APPARATUS FOR TREATING THE EYE.

SPECIFICATION forming part of Letters Patent No. 723,456, dated March 24, 1903.

Application filed May 21, 1901. Serial No. 61,227. (No model.)

To all whom it may concern:

Be it known that I, HENRY FORCE GAREY, a citizen of the United States, residing at the city of Baltimore, State of Maryland, have 5 invented certain new and useful Improvements in Apparatus for Treating the Eye; and I do hereby declare the following to be a full, clear, and exact description of the invention, such as will enable others skilled in 10 the art to which it appertains to make and use the same.

My invention relates to devices for treating diseases of the eyes. The idea of improving defective sight by the repeated and long- 15 continued application of force tending to change the shape of the eyeball has long been familiar; but my method does not depend upon any such ideas, the leading object of my invention being to provide a treatment 20 for that class of diseases of the eyes where nerve stimulation and increased circulation are necessary in order to obtain beneficial results. This object is attained by changing the atmospheric pressure around the eye in 25 such manner as to cause the eye to move outward and inward in the bony walls of its socket, the amplitude of its movements and their number per minute being controlled as desired. The apparatus also provides for 30 varying this treatment in a number of ways.

In the drawings, Figure 1 is a side elevation of the apparatus with certain small portions broken away. Fig. 2 is a plan view of the same devices, a certain cylinder being 35 shown in horizontal section, the plane of section being through its axis. Figs. 3, 4, 5, 6 are detail views of parts seen also in the larger figures. Fig. 7 shows the valve as seen from the left in Fig. 1.

40 In the figures, A represents any suitable bed, which may be of metal, provided with legs A' and strengthening-bars A². Upon this bed is fixed an air-cylinder B, having at its outer end a passage B', communicating 45 with the passage in a flexible tube B². The cylinder is open at the opposite end, and within it works a piston or plunger B³, whose rod B⁴ is guided by a bearing in a bar B⁵, crossing the cylinder's open end diametrically.

50 At the opposite end of the bed a transverse shaft C is mounted in suitable bearings and driven when desired by a pulley C' and a

belt C² from any suitable motor. This shaft bears at its inner end a crank-plate C⁰, having in its face a diametrical recess C³, in 55 which works a non-advancing threaded rod C⁴, arranged to be conveniently rotated when desired, as shown, by a winged projecting head C⁵. This head carries back and forth a block C⁶, fitting in the recess or groove C³ and 60 serving to hold a threaded crank-pin C⁷, which when screwed home presses upon a small block C⁸ and locks the rod C⁴. A pitman D connects the crank-pin to the end of the plunger-rod B⁴, which has at its outer end a sliding bearing D' without novelty. At a point beyond the outer end of the plunger's path a passage E leads from the interior of the cylinder into a valve-chamber F, within which is a rotary valve F' upon a shaft G, parallel 70 to the cylinder, mounted in suitable bearings and driven at the same speed as the shaft C by gears G'. The valve is a cylindrical body 75 adjustably fixed upon its shaft by a set-screw F² and having extending approximately half around its central portion a circumferential groove F³, which when the valve is set as shown registers with the opening E during a part of each revolution of the shaft G. The shaft G is held against longitudinal movement by 80 collars G³ G⁴; but by loosening the set-screw of the former it may slide longitudinally far enough to disengage the gears G', allowing the shaft C to rotate without actuating the valve. When desired, the belt C² may be removed 85 and the apparatus may be actuated by a hand-crank H, driving a swinging shaft H', mounted in a bent lever-yoke H², pivoted at H³ and having its free end carried in one direction by a thumb-screw I and pressed in 90 the opposite direction by a strong spring I'. Upon the shaft H' is fixed a wheel J, intended for frictional engagement with a smaller wheel J' upon the shaft C. To complete the apparatus, a cup K is detachably secured to 95 the free end of the tube B². As shown, this cup is somewhat larger than the eye and is so formed that its margin will closely fit the parts covering the bony structure forming the socket of the eye and prevent the passage 100 of air under these margins to or from the interior of the cup.

It is obvious that by turning the screw I inward the wheel J will be swung from the

wheel J', thereby disconnecting the crank from the shaft C, leaving the latter to be rotated by the belt, and that if the belt be removed and the screw I be turned outward the 5 spring I' presses the wheel J against its companion, bringing the crank into engagement and making of the apparatus a hand-operated machine.

If the shaft G be moved longitudinally to 10 disengage the gears and the valve be in position to close the opening E, the subsequent operation of the machine will cause alternate rarefaction and condensation of the air in the cup K, no air escaping on either stroke of the 15 plunger and the eye itself being alternately drawn outward and returned to its original position. The rapidity of this action depends wholly on the speed of rotation of the shaft C; but the extent of rarefaction and condensation 20 is regulated by the rod C⁴, which varies the distance of the crank-pin from the axis of the shaft, and thus changes the stroke between the limits zero and twice the maximum distance of the crank-pin from that axis. In 25 thus setting forth the action while the valve is not moving with the other working parts it has been supposed that when the plunger is at one end of its path the atmospheric pressure in the cylinder was the same as outside, 30 or normal. This is not, however, necessarily the case, and when it is not results of a radically different character may be produced. Let us suppose that the plunger is at the outer limit of its path and set for a long 35 stroke, the cup being pressed air-tight over the eye and the valve closed and disconnected from its actuating devices. By moving the plunger to the opposite end of its path rarefaction will be caused, and if the screw C⁵ be 40 now turned so as to carry the plunger back until we have the degree of rarefaction desired as the maximum in the immediate further operation of the machine the stroke will be shortened at each end by an amount equal 45 to the distance through which it has just been moved. Consequently the plunger in the further operation of the machine cannot return to the point at which rarefaction began when it was drawn outward—that is, cannot go far 50 enough to bring the pressure in the cylinder back to normal—but can only change the degree of rarefaction between the maximum just established and a less degree or minimum. It follows that if the power-shaft be now rapidly 55 rotated the pressure will oscillate between two different degrees of rarefaction without any compression or even any return to normal atmospheric pressure. The eye will thus be held in front of its normal position, 60 with connected parts—like the optic-nerve, for example—under tension, and while so held it will be oscillated from front to rear. There is in the case just supposed no sudden release by the opening of a valve, but the 65 eye at all times tends to follow the movements of the plunger. In an exactly analogous manner the machine may be adjusted

to oscillate the eye while holding it constantly in the rear of its normal position by keeping the air in front of it compressed. It 70 may also be adjusted to oscillate the eye between either maximum and the normal point or, if desired, between either maximum and a point at a selected distance upon the other side of the normal point. If the gears be in 75 engagement and if the valve F' be so set as to cut off at the instant when the plunger begins its outward or exhausting movement, during the entire outward stroke the plunger acts to gradually exhaust the air from the 80 cup. Then whether this stroke be long or short at the moment when the outward stroke is completed the valve-groove F³ comes into communication with the opening E in the cylinder and the vacuum is instantly destroyed by influx of air through a suitably-located opening L, Fig. 1, in the valve-chamber if the valve be set so that its groove or recess registers for its full width with the opening E. If the valve be so set as to cut 90 off at the beginning of the opposite stroke, the air in the cup is progressively condensed until the stroke is completed, when the opening of the valve suddenly releases the compressed air if the valve registers fully with 95 the opening E. Since the valve, as has been explained, is longitudinally adjustable upon its shaft, it may be moved along so that it constantly closes any desired fraction of the opening E, and thus the influx of air after 100 rarefaction or efflux after compression may be made as gradual as is desired, or the treatment may be more or less gentle so far as releasing the eye can modify it.

If it be desired to rarefy the air on the outward stroke of the plunger, suddenly relieve the partial vacuum, and on the return stroke compress the air and in like manner suddenly release it at the completion of that stroke, the valve F' may be moved to the 110 right by turning its set-screw until two diametrically opposite short grooves O' O' instead of the groove F³ come into the plane of the opening E in the cylinder, so that at the end of each half-revolution the opening 115 E communicates for a short interval with the external air and is closed during the intermediate intervals. In this case also, if desired, the valve may be set so as to have the opening partially closed while air is admitted or released and with results similar to those obtained by a like arrangement when the opening registers with the single groove. It has been explained that by rotating the valve on its shaft and again fixing it it may 125 be made to leave the aperture E open during either the rarefying or the condensing stroke of the plunger. The same result may be somewhat more conveniently attained by means of the screw C⁵ and without the use 130 of any tool or preliminary removal of parts. If the machine be stopped when the plunger is at one end of its path and the valve is at the point of opening or closing and if the

crank-pin be carried to the opposite side of the axis of the crank-plate's center of rotation, the plunger will be carried to the opposite end of its path and will make again the 5 same kind of stroke which it had just completed, the particular action of the valve thus occurring at the beginning instead of at the end of such stroke. We have thus a virtual reversal of the valve, and if the machine before compressed it will now rarefy, and vice versa. It is then quite possible to use the same machine for the various kinds of treatment that the different cases may require and, for example, to so set the crank-pin as 15 to produce a hardly-appreciable vibration of the parts within the cup's rim or to produce any degree of vibration between this and movement that approaches violence, and whatever variation in air-pressure may be 20 chosen the alternations may be as slow or as rapid as the judgment of the physician may require, and the suddenness of the transition may be controlled at will, as may also the total amount of air allowed to enter or escape 25 while the valve is open.

It is evident that the exact construction shown for illustration need not be followed, and I do not, therefore, wish to limit myself to these constructions.

30 What I claim is—

1. The combination with a cup adapted to fit upon parts surrounding the eye, of a cylinder communicating with the interior of said cup and provided with a passage leading to 35 the air without the cylinder, a rotary valve controlling said passage, a crank-shaft, a crank-pin adjustable from side to side of said crank-shaft, and means for locking the crank-pin at any point in its path of adjustment.

40 2. The combination with a cup adapted to fit upon parts surrounding the eye, of a cylinder communicating with the interior of the cup and provided with a passage leading to the external air, a plunger working in the cylinder in position to vary the tension of the air 45 in that part from which said passage leads, an adjustable valve adapted to close said passage constantly when in one position and intermittently when in a different position,

50 means for at will securing the valve in either position, and devices adapted for constant movement and for operating the valve in any of its positions.

55 3. The combination with a cup adapted to fit upon parts surrounding the eye, of a cylinder communicating with the interior of the cup and provided with a passage leading to the external air, a plunger reciprocating in the cylinder to vary the tension in that portion from which the passage leads, a valve 60 controlling said passage and adapted for constant movement, means whereby the valve

closes the passage when the plunger reaches a predetermined point and opens it more or less completely when the plunger reaches another point, and means for at will fixing the degree of such opening.

65 4. The combination with a cup adapted to fit upon parts surrounding the eye, of a cylinder communicating with the interior of the cup and provided with an opening leading to the external air, a rotary valve seated in position for closing said opening and provided with a recess extending partly around its periphery in position to register with said opening as the valve rotates, and automatic means for rotating the valve.

70 5. The combination with a cup adapted to fit upon parts surrounding the eye, of a cylinder communicating with the interior of the cup and provided with a lateral opening leading to the external air, a plunger reciprocating in the cylinder to vary the tension in that part from which the opening leads, a cylindrical valve seated in position to cover said opening, arranged to rotate upon its own axis, and having in certain planes perpendicular to that axis peripheral recesses, and in other parallel planes an unbroken peripheral surface, and means for adjusting the valve longitudinally with reference to its axis to bring either recessed or non-recessed parts into registry with said opening.

75 6. The combination with a cup adapted to fit upon parts surrounding the eye, of a cylinder communicating with the interior of the cup and provided with a lateral opening leading to the external air, a plunger reciprocating in the cylinder, a rotary valve fitting against the cylinder in position to close said opening and having a circumferential recess extending partly around its periphery in the plane of the aperture, and means for rotating the valve in time with the reciprocating plunger to bring the recess in communication with said opening when the plunger reaches predetermined points.

80 7. The combination with the cylinder having a lateral aperture through its wall, of the plunger reciprocating in the cylinder, a shaft mounted alongside the cylinder, a cylindrical valve adjustably fixed upon said shaft and provided with peripheral recesses in different planes perpendicular to the shaft and in position to register with said aperture when the valve is properly adjusted, longitudinally, upon said shaft, and means for rotating the shaft.

In testimony whereof I affix my signature in presence of two witnesses.

HENRY FORCE GAREY.
